MACHINE GUN MOUNT

Don Allen Taylor, Wadsworth, Ohio, assignor of
one-half to F. Walter Boyer, Wadsworth, Ohio

Application April 18, 1936, Serial No. 75,177

4 Claims. (Cl. 89—37)

This invention relates to machine guns, and more particularly to an improved mounting therefor.

An object of the present invention is to provide 5 a mounting for a machine gun which includes means providing for the continuous oscillation of the gun in a horizontal plane.

A further object of the invention is to provide a mounting for machine guns which includes 10 means for providing for a continuous rocking movement of the gun in a vertical plane in addition to a continuous oscillating movement of the gun in a horizontal plane.

The invention, together with its objects and 15 advantages, will be best understood from a study of the following description taken in connection with the accompanying drawings wherein:

Figure 1 is a side elevational view illustrating the application of one form of gun mount;

20 Figure 2 is a top plan view of the gun mount;
Figure 3 is a sectional view through the mounting;

25 Figure 4 is a fragmentary detail sectional view showing the manner of securing the gun on the mounting;

Figure 5 is a fragmentary perspective exploded view showing certain elements hereinafter more fully referred to;

30 Figure 6 is a fragmentary bottom plan view of a cylinder forming part of the mount;

Figure 7 is a detail sectional view showing one of the ear segments;

35 Figure 8 is a view similar to Figure 1 illustrating a slightly modified form of the invention, with certain parts broken away and shown in section;

Figure 9 is a fragmentary detail sectional view illustrating certain details hereinafter more fully referred to.

40 Referring to the drawings by reference numerals, and particularly to the form of the invention shown in Figures 1 to 7, it will be seen that the improved machine gun mount comprises an electric motor indicated generally by the reference 45 numeral 5, and in accordance with the present invention the casing of the motor 5 is constructed so as to provide at one end thereof a gear box. Said casing of the motor is also formed at opposite ends thereof with apertured attaching brackets 7 through the medium of which and suitable fastening elements the motor may be secured to a suitable support.

45 The gear box 6 is suitably provided with aligned bearings 9 and 10, respectively, in which are jour-

naled the ends of the shaft 11 that extends at right angles to the shaft of the motor.

Suitably mounted on the shaft 11 for rotation therewith are spaced gear segments 12 and 13 which are successively engaged by a gear segment 14 provided on one end of the armature shaft of the electric motor. It will thus be seen that when the gear segment 14 is in mesh with the gear 13 the shaft 11 will be rotated for a fraction of a revolution in one direction, and as the gear segment 14 moves out of engagement with the gear segment 13, said gear segment 14 will move into mesh with the gear segment 12 for reversing the rotative movement of the shaft 11.

The shaft 11 at the end thereof journaled in 15 the bearing 9 projects beyond the casing of the motor and at its extended end is provided with a squared socket which receives a squared pin 16 formed on the bottom side of a cylinder 17. The pin 16 is secured within the socket 11a of shaft 11 20 through the medium of set screws or the like 18.

Fitted within the respective apertured ends of 25 the cylinder 17 are bushings 19 which intermediate their ends are provided with flanges 20 that are engaged by flanges on the ends of caps 25 21 and are threaded on the respective opposite ends of the cylinder 17 in a manner clear from a study of Figures 3 and 5. In this manner bushings 19 are securely held within the respective opposite ends of the cylinder 17 and accommodate 30 a rod 22 that extends axially through the cylinder. On an intermediate portion of the rod 22 is a coiled spring 23, the end convolutes of which bear against the inner ends of the bushings 19 and spring 23 serves to absorb the shock, 35 as is apparent.

On the respective opposite ends thereof shaft 22 is provided with tubular cross-heads 24 which are received between pairs of opposed lugs 25 provided on the machine gun, a portion of which 40 is shown in the drawings and indicated generally by the reference numeral 26.

The lugs 25 are suitably apertured and extending through the said apertured lugs 25 and the cross-heads 24 are bolts 27 through the medium 45 of which the machine gun is secured to the rod 22.

From the description of the invention thus far, it will be apparent that when the circuit through the electric motor is closed, the drive will be 50 transmitted from the motor through the gearing 14, 13, on one hand, and the gearing 14, 12, on the other hand for oscillating the shaft 11 and the parts associated therewith in a manner to cause the machine gun 26 to swing first in one 55

direction, then in a reverse direction, or from right to left as the case may be.

It will also be apparent that the gun 26 will be caused to oscillate from the right to the left and vice versa at a rapid rate of speed and accordingly a mounting embodying the features of the present invention will be found especially adapted for use in mounting on airplane machine guns.

For the electric motor there is also provided in accordance with the present invention an automatic starting and stopping switch 29.

In the form of the invention shown in Figures 8 and 9 provision is made for rocking the gun in a vertical plane and to that end instead of providing on the bottom of the cylinder a squared lug as shown and described in the first form of the invention, there extends from the bottom of the cylinder indicated in Figure 8 by the reference numeral 17^a an arm 29 which at its free end 20 has oppositely projecting lateral arms 30.

Also in this second form of the invention there is provided a smaller supplemental electric motor 31 to one end of the casing of which there is bolted or otherwise secured a gear casing 32 which is provided with a depending lug 33 which fits within the socket of the shaft 11 as shown in Figure 8. Thus it will be seen that the motor 31 and associated parts will be so mounted or connected with the shaft 11 as to oscillate there-

30 with.

On the top thereof the casing 32 is provided with an arcuate slot 34 which receives arm 29 and the lateral extensions 30 on the end of the arms are journaled in bearings 35 provided in opposed 35 side walls of the gear casing 32.

On the extensions 30 are gear segments 36 and 37, respectively, and these gear segments are successively engaged and in alternation by a gear segment 38 provided on one end of the armature 40 shaft of the motor 31 as clearly shown in Figure 8.

It will thus be seen that drive from the motor 31 is imparted through the gearings 38 and 36 on one hand and the gearings 38 and 37 on the other hand for oscillating the arm 29 and consequently 45 causing the gun 27 to swing vertically first to one direction and then in a reverse direction.

It will also be apparent that with the arrangement illustrated in Figures 8 and 9, vertical swinging movement of the gun 26 will take place 50 incidental to an oscillatory movement of the gun in a horizontal plane.

Thus with a mounting embodying the features of this invention, a machine gun will have a line of fire covering a great area with the result that 55 this mounting, as before mentioned, will be especially useful in mounting machine guns on airplanes for use under conditions of war.

Having thus described the invention, what is 60 claimed as new is:

60 1. In a device of the character described, an electric motor including a casing having a gear box at one end thereof, a shaft journaled in said gear box and having an end projecting outwardly from the gear box, a pair of opposed spaced gear segments on said shaft, said motor having a shaft terminating within the gear box, and a gear segment on the motor shaft successively engaging the first mentioned gear segments for imparting oscillatory movement to said first named shaft, 65 and means on the outer end of said first named shaft for mounting a machine gun thereon, said means comprising a cylinder attached intermediate its ends to the first named shaft and a

gun supporting rod reciprocably mounted in said cylinder.

2. In a device of the character described, an electric motor including a casing having a gear box at one end thereof, a shaft journaled in said gear box and having an end projecting outwardly from the gear box, a pair of opposed spaced gear segments on said shaft, said motor having a shaft terminating within the gear box, and a gear segment on the motor shaft successively engaging the first mentioned gear segments for imparting oscillatory movement to said first named shaft, a cylinder mounted intermediate its ends on the outer end of said first named shaft, a rod extending axially through said cylinder for reciprocating movement, and a means for attaching a machine gun to said rod at the respective opposite ends of the latter.

3. In a device of the character described, an electric motor including a casing having a gear box at one end thereof, a shaft journaled in said gear box and having a socketed end projecting outwardly from the gear box, a pair of opposed spaced gear segments on said shaft, said motor having a shaft terminating within the gear box, and a gear segment on the motor shaft successively engaging the first mentioned gear segment for imparting oscillatory movement to said shaft, a relatively smaller motor having a gear case on one end, a stud projecting from the second named gear case and fitted in the socket of said first named shaft for oscillating said second named gear case, an arm having an end pivotally mounted within the second mentioned gear case, said arm extending through an arcuate slot in the second mentioned gear case, motion transmitting means connecting the pivoted end of said arm with the second mentioned motor for transmitting swinging movement to said arm first in one direction and then in a reverse direction, and means on said arm for attaching a machine gun thereto.

4. In a device of the character described, an electric motor including a casing having a gear box at one end thereof, a shaft journaled in said gear box and having a socketed end projecting outwardly from the gear box, a pair of opposed spaced gear segments on said shaft, said motor having a shaft terminating within the gear box, and a gear segment on the motor shaft successively engaging the first mentioned gear segments for imparting oscillatory movement to said shaft, a relatively smaller motor having a gear case on one end, a stud projecting from the second named gear case and fitted in the socket of said first named shaft for oscillating said second named gear case, a shaft journaled in the second named gear case also having a pair of opposed spaced gear segments, a gear segment engageable therewith and driven by the second named 60 motor, an arm extending laterally from said last named shaft through an arcuate slot in the second named gear case for transmitting swinging movement to said arm first in one direction and then in a reverse direction, a cylinder connected intermediate its ends to the free end of said arm, a rod extending axially through said cylinder, and means for connecting a machine gun to the respective opposite end of said rod to be supported by said rod for oscillatory movement in a horizontal plane and rocking movement in a vertical plane.

DON ALLEN TAYLOR.
